UNITED STATES PATENT OFFICE.

ANDREW G. STEINBRENNER, OF ST. LOUIS, MISSOURI.

ROLLER SIDE BEARING.

SPECIFICATION forming part of Letters Patent No. 734,990, dated July 28, 1903.

Application filed May 8, 1903. Serial No. 156,202. (No model.)

To all whom it may concern:

Be it known that I, ANDREW G. STEINBRENNER, a citizen of the United States, residing at the city of St. Louis, State of Missouri, have invented a certain new and useful Improvement in Roller Side Bearings, of which the following is a full, clear, and exact description, such as will enable others skilled in the art to which it appertains to make and use the same, reference being had to the accompanying drawings, forming part of this specification, in which—

Figure 1 is a top plan view of my improved roller-bearing with the cap-plate thereof removed, and Fig. 2 is a side elevational view of the completed roller-bearing.

This invention relates to new and useful improvements in roller-bearings adapted to be used as side bearings between the truck-bolster and body-bolster of railway-cars; and it consists in certain improvements in the detail construction and operation thereof, all as hereinafter more fully described, and specifically pointed out in the claims.

This invention relates to that type of side bearing shown in an application filed May 8, 1903, Serial No. 156,201, in which is shown but not claimed some of the features of the side bearing herewith illustrated.

In the annexed drawings, A indicates a truck-bolster; B, a body-bolster; 1, a supporting member bolted or otherwise secured to the truck-bolster; 2, a bearing-plate supported by said supporting member; 3, a longitudinally-extended guard integral with the supporting member 1, and 4 is a trunnion integral with the supporting member 1, extending transversely therefrom beyond the guard 3, upon which trunnion is carried the

gear or segment 5, which is secured in position upon said trunnion by means of the cotter 6 or equivalent securing means. The gear or segment 5 is provided with teeth 7, which mesh with a rack 8, which rack is integral with and projects laterally from the cap-plate 9, with which is connected the bearing-plate 2^a, adapted to rest upon rollers 10 in the carriage 11. Projecting inwardly from the gear 5 is a lug upon which is pivotally supported the link 12, which is in turn connected to the lug 13, projecting laterally from the carriage

11. Owing to the strains both vertical and lateral to which a roller-bearing of this class is subjected it is essential that positively-connected means be provided whereby the carriage, with its friction-reducing rollers or equivalent means, shall be restored positively to operative position as speedily as possible at all times. Hence the importance of the rack 8 meshing with the gear 7 and the connection of the link 12 with the gear and to the carriage, said means effecting such restoration of parts as to adapt the device to operative use at all times.

In practice it has been found that devices heretofore used to accomplish this purpose were defective for various reasons, and to protect these parts in the present invention the guard 3 is provided, which effectually prevents lateral shifting of the carriage 11 against the link 12 or gear 5, which might have a tendency to destroy the effectiveness of said parts or throw them out of operative connection.

In the present side bearing the truck-bolster 75 and body-bolsters are connected, respectively, with the supporting member 1 and bolster-plate 15 by bolts, and, in addition thereto, flanges 16 are provided on the members 1 and 15, which flanges extend vertically a sufficient 80 distance to partially embrace the said bolsters, thereby removing the strain from the bolts 17, used to connect said parts together.

I am aware that minor changes in the construction, arrangement, and combination of 85 the several parts of my device can be made and substituted for those herein shown and described without in the least departing from the nature and principle of my invention.

Having thus described my invention, what 90 I claim as new, and desire to secure by Letters Patent, is—

1. In a roller-bearing, a base-plate, a guard thereon extending longitudinally thereof, a gear supported laterally beyond said guard, 95 a roller-frame movable over said base-plate, a cap-plate movable over said roller-frame, and means on said cap-plate and on said roller-frame whereby they are connected with said gear; substantially as described.

2. In a roller-bearing, a base-plate, a guard thereon integral therewith and extending lon-

5 longitudinally thereof, a gear supported laterally beyond said guard, a roller-frame movable over said base-plate, a cap-plate movable oversaid roller-frame, and means on said cap-plate and on said roller-frame whereby they are connected with said gear; substantially as described.

6 10 3. In a side bearing, a base-plate, a cap-plate, a carriage movable between said plates, a rack on one of said plates, a segment in engagement with said rack, and a guard extending longitudinally between one of said plates and said segment; substantially as described.

15 15 4. In a side bearing, a base-plate, a cap-plate, a carriage movable longitudinally thereof between said plates, a guard projecting longitudinally of one of said plates, a segment rockably supported beyond said guard, a rack on one of said plates in engagement therewith, and a link connecting said carriage with said segment; substantially as described.

20 25 5. In a side bearing, a member carried by the truck-bolster, a carriage mounted on said member, a toothed, rockable member connected with said member, a cap-plate with a downwardly-extending rack thereon engaging said rockable member, and a link connecting the carriage with said rockable member; substantially as described.

25 30 6. In a side bearing, a support adapted to be carried on the truck-bolster, a laterally-extending part integral therewith, a gear rockable on said part, a carriage connected with said gear, and a cap-plate in engagement with said gear; substantially as described.

35 40 7. In a side bearing, a support adapted to be carried on a truck-bolster, a rockable gear supported thereby, a carriage on said support, a link connecting said carriage with said gear, and a cap-plate above said carriage with a downwardly-extending rack engaging said gear; substantially as described.

45 50 8. In a side bearing, a support adapted to be carried on a truck-bolster, a rockable gear supported thereby, a carriage connected positively with said gear, a cap-plate slidably mounted on said carriage, and a rack extending vertically from said cap-plate in constant mesh with said gear; substantially as described.

55 9. In a side bearing, a base-plate, a roller-frame, rollers therein, a cap-plate, a rack on one of said plates, a segment on the other of said plates in mesh with said rack, and a link

connecting said segment with said roller-frame; substantially as described.

10 60 In a side bearing, a base-plate, a roller-frame slidably interlocked therewith, rollers therein, a cap-plate, a rack on one of said plates, a segment on the other of said plates in mesh with said rack, and a link connecting said segment with said roller-frame; substantially as described.

11 65 In a side bearing, a base-plate, a roller-frame, rollers therein, a cap-plate movably connected with said roller-frame, a rack on one of said plates, a segment on the other of said plates in mesh with said rack, and a link connecting said segment with said roller-frame; substantially as described.

12 70 In a side bearing, a base-plate, a roller-frame slidably interlocked therewith, rollers therein, a cap-plate movably connected with said roller-frame, a rack on one of said plates, a segment on the other of said plates in mesh with said rack, and a link connecting said segment with said roller-frame; substantially as described.

13 75 In a side bearing, a base-plate, a roller-frame, rollers therein, a cap-plate, a rack on one of said plates, a segment pivotally supported laterally of and on the other of said plates in mesh with said rack, and a link connecting said segment with said roller-frame; substantially as described.

14 80 In a side bearing, a base-plate, a bearing-surface thereon, a roller-frame movable over and interlocked with means projecting laterally above a portion of said base-plate, a cap-plate, a rack thereon, a segment pivotally connected with said base-plate in engagement with said rack, and a link connecting the roller-frame with said segment; substantially as described.

95 145 15. In a side bearing, a base-plate, a cap-plate, friction-reducing means, a movable frame guiding said friction-reducing means, an integral extension on one of said plates, a rack on the other thereof, a gear on said extension in engagement with said rack, and a link connecting said gear with said movable frame; substantially as described.

150 In testimony whereof I hereunto affix my signature, in the presence of two witnesses, this 5th day of May, 1903.

ANDREW G. STEINBRENNER.
